(57) **CLAIM**

The ornamental design for an implant removal tool, as shown and described.

DESCRIPTION

FIG. 1 is a perspective view of a design for an implant removal tool;

FIG. 2 is a front view of the design for the implant removal tool of FIG. 1;

FIG. 3 is a back view of the design for the implant removal tool of FIG. 1;

FIG. 4 is a first side view of the design for the implant removal tool of FIG. 1;

FIG. 5 is a second side view of the design for the implant removal tool of FIG. 1;

FIG. 6 is a top view of the design for the implant removal tool of FIG. 1; and,

FIG. 7 is a bottom view of the design for the implant removal tool of FIG. 1.
